(57) **CLAIM**

We claim the ornamental design for a lint trap, as shown and described.

DESCRIPTION

FIG. 1 is a front perspective view of a lint trap showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

FIG. 9 is a cross-sectional view of the lint trap taken through line 9-9' of FIG. 2;

FIG. 10 is an enlarged view of the encircled portion shown in FIG. 3 labeled 10; and,

FIG. 11 is an enlarged view of the encircled portion shown in FIG. 9 labeled 11.

The broken lines in the figures show portions of the lint trap which form no part of the claimed design.

The dot-dash broken lines encircling portions of the claimed design that are illustrated in enlargements form no part of the claimed design.
